DESIGN FOR A TIRE

Harold V. James, Denver, Colo.

Application July 12, 1938, Serial No. 78,416

Term of patent 7 years

To all whom it may concern:

Be it known that I, Harold V. James, a citizen of the United States, residing at Denver, in the county of Denver and State of Colorado, have invented a new, original, and ornamental Design for a Tire, of which the following is a specification, reference being had to the accompanying drawing, forming part thereof.

In the drawing:

Fig. 1 is a perspective view of a tire showing my new design.

Fig. 2 is a plan view thereof.

Fig. 3 is a radial cross-section therethrough.

I claim:

The ornamental design for a tire, as shown.

HAROLD V. JAMES.
